UNITED STATES PATENT OFFICE.

OSCAR A. KNIGHT, OF GLACIER, WASHINGTON.

SPLICING BENCH.

Application filed September 19, 1922. Serial No. 589,264.

To all whom it may concern:

Be it known that OSCAR A. KNIGHT, a citizen of the United States of America, residing at Glacier, in the county of Whatcom and State of Washington, has invented new and useful Improvements in Splicing Benches, of which the following is a specification.

The object of the invention is to provide a comparatively simple and efficient apparatus for splicing or putting terminal loops or eyes in cables and particularly wire cables; and with this object in view the invention consists in a construction and combination of parts of which a preferred embodiment is shown in the accompanying drawings, wherein:—

Figure 1 is a side view, and

Figure 2 is a longitudinal sectional view of a splicing apparatus embodying the invention.

Figure 3 is a transverse sectional view on the plane indicated by the line 3—3 of Figure 2.

Figure 4 is a detail view of the cylinder.

Figures 5 and 6 are similar views of the feed screw and follower respectively.

Figure 7 is a transverse sectional view on the plane indicated by the line 7—7 of Figure 2.

The apparatus consists essentially of a cylinder 10 revolvably mounted upon a suitable supporting frame consisting in the construction illustrated of a base 11 having a standard 12 provided with a sleeve bearing 13 in which the cylinder is mounted and which is provided with means for engaging a cable 14 which is to be spliced or in an end of which is to be formed a splice eye or loop. Preferably a clamping device in the nature of a vise 15 is supported by the base at a point remote from the cylinder and in alignment therewith for clamping and holding the body portion of the cable during the splicing operation.

The means carried by the cylinder for engaging the cable consist of a follower fitted in an axial guide opening 17 in the cylinder and provided with a terminal hook 18, together with a feed or jack screw 19 having a swivelled bearing against one end of the cylinder and threaded into a bore of the follower, so that the rotation of the feed screw serves to cause a lineal axial movement of the follower of which the terminal hook is

engaged with the cable. The screw is provided with a cross arm operating handle 20, and the end of the cylinder adjacent to the hook 18 is provided with a funnel shaped cavity 21 into which the engaged bight of the cable is drawn to give the desired bend or loop thereto and bring the loose end of the cable back to a position adjacent to the body portion of the cable so as to facilitate the engagement of the terminals of the strands with the body portions of the strands in the formation of the splice.

In order to loosen the strands of the body portion of the cable to facilitate the passing of the terminals of the strands thereunder the cylinder is adapted to be rotated or turned in the direction of unwinding or untwisting the cable strands while the body portion of the cable is held by the clamp 15. To this end one of the terminal flanges of the cylinder is provided with a handle 23, and in order that the cylinder may be locked in its adjusted positions to hold the cable in the untwisted or loosened condition during the splicing operation a locking pin 24 is provided for engagement with an opening 25 in the sleeve bearing 13 and one of a series of corresponding openings 26 in the cylinder.

Having engaged the cable at a sufficient distance from the end in which the loop is to be formed by means of the clamp 15 and having passed the end of the cable through the hook 18 the feed screw should be operated to draw the loose end of the cable into the socket or cavity 21 to cause the proper kink or bend therein as above indicated, whereupon the cylinder should be turned by means of the handle 23 to sufficiently untwist or loosen the strands of the body portion of the cable between the hook 18 and the clamp 15 so that through the use of the Marlin spike or like tool employed in this connection the extremities of the strands at the free end of the cable may be inserted under the body portion of the cable. This having been accomplished the cylinder may again be turned in one direction or the other as desired to facilitate the engagement of the free ends of the engaged strands with other strands to complete the lock or splice, after which the loop thus formed may be released from the follower.

Having described the invention, what is claimed as new and useful is:—

- 2
1. A splicing apparatus having a rotary cylinder and means carried thereby for engaging and kinking the cable to form a loop or eye therein and dispose the extremities of the cable adjacent to the line of the body portion thereof, together with means for locking the cylinder in its adjusted positions. 30
  2. A splicing apparatus having a rotary cylinder and means carried thereby for engaging and kinking the cable to form a loop or eye therein and dispose the extremities of the cable adjacent to the line of the body portion thereof, together with means for locking the cylinder in its adjusted positions, means being provided for clamping the body portion of the cable at an interval from the end thereof to prevent the turning of the same during the rotation of the cylinder. 35
  3. A splicing apparatus having a rotary cylinder and means carried thereby for engaging and kinking the cable to form a loop or eye therein and dispose the extremities of the cable adjacent to the line of the body portion thereof, consisting of a follower provided with a terminal cable-en-
  - gaging hook, and a feed screw for actuating said follower, the cylinder being provided with a funnel-shaped kinking cavity. 40
  4. A splicing apparatus having a rotary cylinder and means carried thereby for engaging and kinking the cable to form a loop or eye therein and dispose the extremities of the cable adjacent to the line of the body portion thereof in combination with a base having a sleeve bearing in which the cylinder is mounted, the cylinder being terminally flanged beyond the extremities of said bearing. 45
  5. A splicing apparatus having a rotary cylinder and means carried thereby for engaging and kinking the cable to form a loop or eye therein and dispose the extremities of the cable adjacent to the line of the body portion thereof in combination with a base having a sleeve bearing in which the cylinder is mounted, and cylinder locking means consisting of a pin and registerable openings respectively in the cylinder and the bearing. 50

In testimony whereof he affixes his signature,

OSCAR A. KNIGHT.
